UNITED STATES PATENT OFFICE.

CHARLES F. BAILEY, OF PEORIA, ILLINOIS, ASSIGNOR TO KEYSTONE STEEL & WIRE COMPANY, OF PEORIA, ILLINOIS, A CORPORATION OF ILLINOIS.

WIRE-FEEDING MECHANISM.

1,275,984.

Specification of Letters Patent. Patented Aug. 13, 1918.

Application filed October 6, 1916. Serial No. 124,110.

To all whom it may concern:

Be it known that I, CHARLES F. BAILEY, a citizen of the United States, residing at Peoria, in the county of Peoria and State of Illinois, have invented new and useful Improvements in Wire-Feeding Mechanism, of which the following is a specification.

This invention has reference to certain new and useful improvements in wire working machines, and particularly to that type of fabricating machines used in the manufacture of farm, field and poultry fences.

One of the objects of the present invention is to improve the stay wire feeding mechanism shown in the patent issued to W. H. Sommer, No. 1,093,578, dated April 14, 1914.

In the Sommer patent referred to the co-operating friction feeding wheels are driven by a clutch controlled gear wheel. My invention contemplates the use of friction feeding wheels, and the doing away of the clutch controlled driving means, and the operation of one of the friction feeding wheels by a driving means which will rotate said feeding wheel first in one direction and then in the opposite direction, or, in other words, alternately rotate said feeding wheel in opposite directions; the co-acting feeding wheel arranged to be moved into operative relation with the alternately rotating feeding wheel at the beginning of each rotation of said feeding wheel in a direction for feeding a stay wire into the machine.

The invention has for a further object to provide a pair of feeding wheels which are adapted to co-act upon a stay feed wire; one of said feeding wheels adapted to be driven by means which will alternately rotate said feeding wheel first in one direction and then in the opposite direction, and in the employment of means for moving the other feeding wheel into operative relation with said driven wheel each time said feeding wheel is rotated in a direction to feed the stay-feed wire, and for moving said feed wheel out of operative relation with said driven feed wheel each time said feed wheel is rotated in a non-feeding direction, and for clamping the stay feed wire when said feeding wheels are in non-operative relation.

A further object of the invention is to provide a pair of feeding wheels, a driv-

ing gear wheel, and means for rotating said driving gear wheel alternately in opposite directions, said driving gear wheel being geared to one of said feeding wheels whereby said feeding wheel will be caused to rotate alternately in opposite directions with said driving gear wheel, and means for moving said other feed wheel into operative relation with said driving feed wheel when said wheel is rotated in a feeding direction and out of operative relation therewith when said driving feed wheel is rotated in an opposite direction, and means for clamping the stay feed wire when said feeding wheels are in inoperative relation one with the other.

In the drawings, the fence machine upon which my improvements are shown is illustrated in a fragmentary way only, it being understood that the invention is applicable to various types of fence machines, and I therefore do not wish to be confined to the application of the invention to any particular type of machine.

Figure 1 is a partial plan view of the machine.

Fig. 2 is a side elevation of Fig. 1.

Fig. 3 is a vertical sectional view as the same would appear if taken on the line 3—3 of Fig. 1 looking in the direction of the arrow.

Fig. 4 is a detail plan view partially in section showing the feeding wheels and co-operating parts, and

Fig. 5 is a detailed side elevation partly in section of the means for moving one of the feeding wheels into and out of operative relation with the other feeding wheel and the clamping means for the wire.

The framework of the machine comprises in part the base members 1, the uprights 2 supporting the table 3; the standards 4, 5 and 6, and the cross piece 7. The parts designated 1, 2, 5, and 6 are duplicated upon opposite sides of the machine, and on the base members 1 may be supported a platform (not shown) on which an operator 100 may stand.

8 designates a timing shaft adapted to be driven in a suitable manner from a driving shaft, not shown, and 9 designates a crank shaft suitably journaled in the frame of 105 the machine, and on said crank shaft

is a sprocket wheel 10 engaged by a sprocket chain 11 which is driven by a sprocket wheel 12 on the timing shaft 8, said sprocket chain passing over an idler 5 wheel 13 journaled on the upright 4. It is obvious that when the timing shaft 8 is in motion it will transmit, through the sprocket chain and wheels referred to, motion to the crank shaft 9.

- 10 The wire connecting mechanism, the strand or line wire feeding mechanism, pull-out and wrapping reel, are all omitted from the drawing, together with the means for severing a stay wire from the stay feed wire.
- 15 The mechanisms just enumerated are common to all wire fence machines, except as to their details of construction, and as such mechanisms form no part of the invention except as the invention may be associated 20 therewith, it has not been thought necessary to illustrate the same.

The stay feeding wheels are designated 14 and 15, the former being the driving feed wheel and the latter the driven feed wheel. 25 The bearing for the driving feed wheel 14 has a fixed position on the machine, whereas the bearing for the driven feed wheel 15 is movable so that said feed wheel 15 may be moved into and out of operative relation 30 with the feeding wheel 14.

The feeding wheels referred to are adapted to coact upon a stay feed wire A to feed the same into the machine, the stay feed wire being fed in between the peripheral 35 friction gripping surfaces of said feeding wheels, which may be circumferentially grooved if desired. The stay feed wire A may be fed from a bundle, spool, or in any other suitable manner, and caused to 40 be drawn through straightening rolls, not shown, if desired.

The feeding wheel 14 is journaled on a short vertically disposed shaft 16 which has a bearing in the table 3, or some other suitable frame part of the machine, and on said 45 short shaft 16 and above said feeding wheel 14 and in juxtaposition thereto is carried a gear wheel 17, said gear wheel, its shaft and the driving feeding wheel 14 all being adapted 50 to be rotated in unison when power is imparted to said gear wheel 17. The driven feeding wheel 15 is journaled on a short vertically disposed shaft 18 which said shaft has a bearing in a frame 19 which is pivotally connected at 20 to the table 3 or some other suitable frame part of the machine. The forward end of the frame 19 is formed with or has connected thereto an elongated 55 tubular part 21 normally disposed tangentially to the gripping feeding surfaces of the driving and driven feeding wheels 14 and 15. In this tubular part 21 is carried a bushing 22 having a longitudinally arranged opening 23 therethrough for the 60 passage of the stay feed wire A. This

bushing extends forwardly of the tubular part 21 in between the gripping surfaces of the feeding wheels 14 and 15 to form a guide for the stay feed wire A to the point of contact of the said feeding wheels upon said wire, and on the opposite sides of said feeding wheels is a guide 24 to properly direct the stay feed wire A as it is fed by the feeding wheels, to the wire connecting mechanisms whether they be coilers, loopers or die 75 mechanisms. The opposite end of the bushing 22 protrudes from the tubular part 21 and one side thereof is cut away to form a shoulder 25 and a bearing surface 26, for purposes which will be further explained. 80 Connected to and extending at right angles from said tubular part 21, is a stem 27. This stem at its outer end passes through a guide 28 and also through the upper end of a lever 29 which is fulcrumed at 30 on a suitable frame part of the machine, the other end of the lever 29 having journaled thereon a roller 31 adapted to ride upon the cam surface of a cam wheel 32 on the timing shaft 8. On the stem 27 between the guide 90 28 and a nut 33 on the stem, there is a coil spring 34, which exerts pressure to keep the tubular part 21 in a normal position for the feeding of the stay feed wire and the feeding wheel 15 in a position to coöperate with the 95 feeding wheel 14 to feed said stay feed wire into the machine. On the outer end of the stem and adapted to have a bearing relation with the end of the lever 29 through which the stem passes, are locking and adjusting nuts 35. When the feeding wheels 14 and 15 are coöperating upon the stay feed wire A to feed it into the machine, the roller 31 on the lever 29 is riding over the peripheral surface 36 of the cam wheel 32 100 and when the right amount of stay feed wire has been fed to provide a stay length which is to be severed from the stay feed wire, the frame 19 is oscillated to move the feeding wheel 15 a slight distance, but sufficient to 105 move it out of operative relation with the feeding wheel 14 which will stop the infeeding of the stay feed wire. The frame 19 is moved when the roller 31 on the lever 29 110 rides onto the peripheral surface 37 of the cam wheel 32, which will oscillate the lever 29, and said lever bearing against the locking and adjusting nuts 35 will move the stem 27 and with it the tubular part 21 and the frame 19, resulting in the feed roll 15 115 being moved out of operative relation with the feeding wheel 14. The parts will remain in this non-feeding relation until the roller 31 rides off of the peripheral surface 37 of the cam wheel 32 onto the peripheral 120 surface 36 of said cam wheel, and such movement will permit the spring 34, which has been contracted, to expand moving the tubular part 21 and the frame 19 to a position 125 which will cause the feeding roller 15 to 130

again impinge upon the stay feed wire A and coöperate with the feed roll 14, feeding in a stay length of said stay feed wire.

When the feeding wheel 15 is moved out of operative relation with the feeding wheel 14, in the manner described, it is desirable to clamp the stay feed wire A against forward or rearward movement, and this is accomplished by means of a plunger 38 connected with a stem 39 having a bearing in a suitable frame part of the machine, a spring 40 being coiled about the stem of the plunger and bearing against said plunger and a shoulder on the frame part to hold said plunger in a forward yielding position, locking nuts 41 being used to adjust the position of said plunger. When the stem 27 is moved outwardly through the action of the lever 29 when the roller 31 rides onto the peripheral surface 37 of the cam 32, it will move the tubular part 21 and its bushing 22 toward the end of the plunger 38 and cause the stay feed wire A to be firmly clamped between the end of the plunger and the bearing surface 26 of the bushing 22, the plunger having a bearing on the shoulder 25 of the bushing as said bushing is moved. It will therefore be seen that simultaneously with the movement of the feeding wheel 15 out of operative relation with the feeding wheel 14 the stay feed wire A will be clamped and positively held until it is desirable to feed another stay length across the machine, and at this moment, when the feeding wheel 15 is returned to its coöperative relation with the feeding wheel 14, the stay feed wire A is released from its clamp to permit it to be fed into the machine by means of the stay feeding wheels 14 and 15.

The stay feeding wheel 14 is in continuous operation during the operation of the machine and said feeding wheel 14 is positively actuated, being alternately rotated first in one direction and then in an opposite direction. The feeding wheel 14 being rotated to the right, looking at Fig. 4, it will, assisted by the feeding wheel 15 feed the stay feed wire A a sufficient distance across the machine to provide a stay wire or stay length adapted to be attached to the strand or line wires of the fence. Immediately upon a stay wire or stay length being fed across the machine, the feeding wheel 15 is moved out of operative relation with the feeding wheel 14, and the direction of rotation of said feeding wheel 14 is reversed. To operate the feeding wheel 14 I provide a preferably vertically disposed tubular shaft 42 journaled in suitable bearings on the machine. On the lower end of this shaft is carried a gear wheel 43 in mesh with a rack-bar 44. On the upper end of said shaft 42 is an annular plate 45 having a hub 46 keyed or otherwise suitably secured to said shaft. This annular plate 45 is provided with an annular shoulder 47 removed a short distance inwardly from the periphery of the plate to form a seat 48 to receive an annular flange 49 disposed inwardly of a ring 50 formed on its periphery with teeth 51 adapted to mesh in the teeth of the gear wheel 17. This ring 50, which in reality is a gear, has its connection with the shaft 42 through the plate 45, the ring 50 being placed upon the plate 45 and locked in position thereon by means of bolts 52, said bolts passing through the plate 45 and through a bar 53 which is locked against the upper surfaces of the plate 45 and the annular flange 49 of the ring 50, said flange having a bearing upon the seat 48 and against the shoulder 47 of said ring 50.

The object of making this ring or gear wheel 50 in the form in which it is shown in the drawings is for the purpose of adjusting the driving feeding wheel 14 and to take up any wear occasioned by the continuous engagement of one portion of the peripheral surface of said feed wheel 14 with the stay feed wire. By releasing the nuts on the bolts 52 the ring 50 may be slipped around on the annular plate 45 and said nuts again tightened up for the purpose of clamping the bar 53 firmly against said annular plate and ring. In this way the feeding wheel 14 may be adjusted to present a new wearing surface on the stay feed wire.

The rack-bar 44 which is in mesh with the gear wheel 43 carried on the lower end of the shaft 42, and by means of which movement is transmitted to said shaft, is movable in a guide 54 coincident with the gear wheel 43, and at its inner end said rack-bar 44 is secured to a slidable head 55 having, preferably, a dovetailed connection with and movable on a bar 56 supported by a bracket 57 at one end secured to the part 1, see Fig. 2, and at its opposite end secured upon an arm 58 attached to the upright 4. Pivotally connected at 59 with the slidable head 55 is a pitman bar or rod 60, and said bar 60 has pivotal connection at 61 with a nut 62. This nut 62 is carried upon a threaded rod 63, which said rod is in turn carried or disposed in a longitudinal opening 64 formed in a crank arm 65 carried by the crank shaft 9, see Fig. 2. The threaded rod 63 at its outer end passes through a cap plate 66 and has a squared end 67, whereby a suitable tool may be used to engage the end 67 of the rod 63 for turning said rod and thereby adjusting the nut 62 on the said rod. It is understood, although not shown, that the nut 62 is carried in the opening 64 of the crank arm 65 in the manner which will prevent its rotation when the rod 63 is operated for the purpose of adjusting said nut 62 back and forth on the rod 63. The crank arm 65 rotates with the shaft 9 and it is obvious

that if the nut 62 is adjusted toward and from the axis of the shaft 9, the stroke of the rack-bar 44 will be in turn adjusted. In other words, the closer to the axis of the 5 shaft 9 is carried the nut 62, the shorter the stroke of the rack-bar 44, and the farther from the axis of the said shaft 9, the greater the stroke of the rack-bar 44. The rack-bar and the operating connections between said 10 rack-bar and the crank arm on the crank shaft 9 do not differ materially, either in construction or operation, from the similar mechanism shown in the Sommer Patent 1,093,578 above referred to, and particularly 15 in Fig. 2 of said patent.

What I claim is:—

1. In a fence machine, in combination, a pair of feeding wheels, a driving means for one of said wheels which will alternately 20 rotate said wheel in opposite directions, and means for moving said other feeding wheel into operative relation with said first feeding wheel as it is rotated in one direction and for moving said feeding wheel out of 25 operative relation with said first feeding wheel as it is rotated in an opposite direction.

2. In a fence machine in combination, a pair of feeding wheels, a driving means for 30 one of said wheels which will alternately rotate said wheel in opposite directions, means for moving said other feeding wheel into operative relation with said first feeding wheel as it is rotated in one direction 35 and for moving said feeding wheel out of operative relation with said first feeding wheel as it is rotated in an opposite direction, and means for clamping the wire to be fed by said feeding wheels when said feeding wheels are in non-coactive relation with 40 said wire.

3. In a fence machine, in combination, a pair of feeding wheels, one of said feeding 45 wheels having a relatively fixed position on said machine, a driving means for said wheel which will alternately rotate the same in opposite directions, a movable support on which said other feeding wheel is journaled, and means for moving said support to present the feeding wheel journaled thereon 50 into operative relation with said first feeding wheel as it is rotated in a feeding direction, and for moving said support and said feeding wheel out of operative relation with 55 said first feeding wheel as it is rotated in a on-feeding direction.

4. In a fence machine, in combination, a pair of feeding wheels, a rack-bar geared to one of said wheels to rotate said feeding wheel alternately in opposite directions, 60 means for reciprocating said rack-bar, and means for moving said other feeding wheel into operative relation with said first feeding wheel as it is rotated in a feeding direction and for moving said other feeding wheel out of operative relation with said first feeding wheel as it rotated in a non-feeding direction, a wire guide, and means 65 co-acting with said wire guide to clamp the wire as said first feeding wheel is rotated 70 in a non-feeding direction.

5. In a fence machine, in combination, a pair of feeding wheels, means for rotating one of said wheels in a feeding direction and alternately in a reverse direction, and 75 means for moving said other wheel into wire coacting relation with said first-mentioned feeding wheel coincidently with the rotation of said feeding wheel in a feeding direction, and for moving said second wheel out of 80 wire coacting relation with said first-mentioned feeding wheel coincidently with the reversing of the same.

6. In a fence machine, in combination, a pair of feeding wheels, a gear wheel connected to one of said wheels, a shaft, a gear wheel on said shaft in mesh with said feeding wheel gear, a rack-bar geared to said shaft, a crank-shaft, connections between 85 said crank-shaft and said rack-bar for reciprocating said rack-bar, and means for moving said other feeding wheel into and out of wire coacting relation with said first feeding wheel, the movement of said second feeding wheel out of wire coacting relation 90 with said first feeding wheel occurring coincidently with the reversing of said first feeding wheel.

7. In a fence machine, in combination, a pair of feeding wheels, one a driver and 100 the other a driven wheel, said driving wheel including an annular plate member and a ring-gear, means for adjusting said ring-gear on said annular plate, means for alternately rotating said driving wheel in a feeding direction and in a reverse direction, and means for moving said driven wheel out of 105 wire coacting relation with said driving wheel coincidently with the reversing of the same.

CHARLES F. BAILEY.
